ATTORNEY.

UNITED STATES PATENT OFFICE.

EUSTACE CREEES AND CHARLES S. COURT, OF PROVIDENCE, RHODE ISLAND,
ASSIGNORS TO WIGHTMAN AND HOUGH COMPANY, A CORPORATION OF
RHODE ISLAND.

DESIGN FOR A LOCKET OR SIMILAR ARTICLE.

No. 38,491.

Specification for Design.

Patented March 26, 1907.

Application filed February 21, 1907. Serial No. 358,755. Term of patent 3½ years.

To all whom it may concern:

Be it known that we, EUSTACE CREEES and CHARLES S. COURT, both citizens of the United States, and both residing at Providence, in the county of Providence and State of Rhode Island, have invented a certain new, original, and ornamental Design for a Locket or a Similar Article, of which the following is a specification, reference being had therein to the accompanying drawing.

The figure is a plan view of a locket, showing our new design.

We claim—

The ornamental design for a locket or a similar article as shown.

EUSTACE CREEES.
CHARLES S. COURT.
